Attorney.

UNITED STATES PATENT OFFICE

EVAN C. HARTER, OF STURGES, MICHIGAN, ASSIGNOR TO WILLIAM S. FERRIS, TRADING AS DO/MORE CHAIR COMPANY, OF ELKHART, INDIANA

CHAIR

Application filed May 22, 1929. Serial No. 365,010.

This invention relates to improvements in chairs and it consists of the matters herein-after described and more particularly pointed out in the appended claims.

5 The chair with which my invention is particularly concerned includes a seat and a back rest adjustable thereon by means of supporting arms and braces connecting the arms to the seat. In such a chair the objection has 10 been to the manner of adjustably securing the braces with respect to the seat, mainly because of the time required for making such an adjustment which necessitates the complete removal of a screw from one of a set 15 of holes to another one in said set.

The primary object of the invention is to provide a simple improved means whereby the brace arms may be quickly and easily adjusted with respect to the seat and this with 20 only the loosening of the associated screws instead of the complete removal of said screws as heretofore.

Another object of the invention is to provide in a chair of this kind a structure where- 25 in one end of each brace is adjustably secured to a flange fixed with respect to the seat, by means of a runner or clamping nut slidable in a slot in said flange and operable to se- 30 curely hold said screws in notches or recesses opening into one side of said slot.

The above mentioned objects of the invention as well as others together with the many advantages thereof will more fully appear as I proceed with my specification.

35 In the drawings:—

Fig. 1 is a perspective view of a chair seat and associated back rest supporting structure embodying my invention.

40 Fig. 2 is a view in side elevation on an enlarged scale, of the seat, and bottom end of the back rest supporting arm, together with the brace and means for adjustably securing the same to the chair seat.

45 Fig. 3 is a transverse vertical detail sectional view on a further enlarged scale as taken on the line 3—3 of Fig. 2.

Fig. 4 is a view similar to Fig. 3 with the parts in a changed relation.

50 Fig. 5 is a perspective view of a certain

runner plate or nut embodied in my invention.

Referring now in detail to that embodiment of the invention, illustrated in the accompanying drawing:—1 indicates as a whole a 55 chair seat which as shown herein is rectangular in plan and is preferably made of laminated wood. Said seat which is wider than it is deep is concaved at its mid portion from front to rear and is shown herein as mounted upon a centrally disposed seat post 2 by means of a spider 3. To the bottom surface of each side margin of the seat is secured an angle bar including a horizontal flange 4 and a depending vertical flange 5. The flange 4 is secured to the seat margin by means of bolts 6 in a manner disposing the outer face of the vertical flange 5 substantially in the plane of the edges of said seat margin. Said vertical flange 5 begins at its rear end substantially 60 flush with the rear edge of the seat and terminates at its front end a distance spaced from the front edge of the seat as best shown in Fig. 2. In said vertical flange is provided a longitudinal slot 7, the bottom edge of which 70 is straight while the top edge is undulatory as defined by alternating recesses and projections 8 and 9 respectively. 75

10—10 indicates a pair of back rest supporting arms, one disposed at each side of the 80 chair. Each arm is made of strap metal and in the bottom end of each arm is a plurality of longitudinally spaced holes 11—11 the desired one of which may be registered with a like hole in the rear end of the associated vertical flange 5 to receive a pivot bolt or screw 12. The top portion of each arm is offset inwardly to pivotally receive between them, a back rest member 13. In this respect it is 85 pointed out that the back rest arm may be raised and lowered and may be swung forwardly or rearwardly to accurately adjust the back rest into the desired position with respect to the seat.

14—14 indicates the back rest arm braces, 90 with one associated with each arm. Each brace is made of flat strap metal, slightly curved in the plane of its edges and one end of each arm is pivotally connected as at 15 to the associated arm 10. The other end of said 95 100

brace is adjustably connected to the associated angle bar flange 5 in a manner now to be described.

16 indicates a runner member, in the form of a plate of substantially L shaped cross section which includes a body 17 with a bottom flange or lip 18 that extends slightly upwardly to have a wedging action as will later appear. This member is of a length greater than its height which height approximates the distance between the planes of the straight bottom edge of slot 7 and the underside of the angle bar flange 4. In the body 17 midway between its ends and adjacent the flange on the lip 18 is a threaded opening 19 to receive a screw 20 for connecting the bottom end of the brace bar 14 to the runner member. It is herein pointed out that the screw 20 is of a diameter to fit in any of the recesses 8 at one side of the slot 7 and that distance between the straight edge of the slot and the bottom portion of the projections 9 approximates said diameter.

When the runner member 16 is in place, it occupies a position on the inner side of the flange 5 and when the screw 20 is drawn up snug and occupies one of the notches 8, the top edge of the runner 16 substantially engages the underside of the flange 4 and the lip 18 engages upon said bottom straight edge of said slot all as best shown in Fig. 3.

To adjust the position of the arms 10, the screw 20 associated with each arm brace is loosened but not withdrawn from the runner so that the lip thereof may be removed from the associated slot 7 as shown in Fig. 4 which brings the screw 20 into engagement with the bottom of the slot so that it can be moved there along into a position in line with the desired recess 8. The screw 20 is then tightened up and in this manipulation of the screw, the runner is raised or elevated and the beveled lip thereof will enter the slot and force the screw home into said desired recess so that the adjacent projections act as shoulders, preventing further movement of the screw longitudinally of the slot.

Thus the screw does not need to be removed and replaced but only need be loosened so that the time required to adjust the position of the back rest is materially reduced. The parts are few in number, easy to manipulate and are efficient for their intended purpose.

While in describing the invention, I have referred in detail to the form, arrangement and construction of the various parts thereof, the same is to be considered merely as illustrative so that I do not wish to be limited thereto except as may be specifically set forth in the appended claims.

I claim as my invention:—

1. A chair embodying therein, a seat, a back rest supporting arm pivoted with respect to one end of the seat, a brace pivoted at one

end to said arm, means providing a flange along one side of said seat having a longitudinal slot therein, a member longitudinally adjustable with respect to one side of said flange and having a beveled portion to engage a part of said slot and a screw operatively connecting the other end of the brace to said member.

2. A chair embodying therein, a seat, a back rest supporting arm pivoted with respect to one end of the seat, a brace pivoted at one end to said arm, means providing a flange along one side of said seat having longitudinal slot therein with recesses disposed in one side of said slot, a member disposed on the inner side of said flange and longitudinally adjustable with respect thereto, which member has a beveled portion cooperating with the other side of said slot and a screw operatively connecting the other end of said brace with said member and being actuated by said member in the tightening of the screw to force said screw into one of said recesses.

3. A chair embodying therein a seat, an angle bar fixed to the bottom of said seat along one side thereof and including a depending flange with a longitudinal slot therein having spaced recesses along its top edge, a back rest arm pivoted to the rear end of said flange, a brace pivoted at one end to said arm, a plate disposed on the inner side of said flange and including a lip to engage the bottom edge of said slot and a screw operatively connecting the other end of the brace with said plate.

4. In a chair, means providing a flange with a longitudinal slot therein, having spaced recesses in its top edge, a back rest arm pivoted to the rear end of said flange, a brace pivoted at one end to said arm, a plate longitudinally adjustable with respect to said flange and having a beveled lip along its bottom to engage the bottom of the slot and a screw operatively connecting the other end of said brace and plate member and so operating upon said plate in the tightening up of the screw as to force said screw into one of said recesses.

In testimony whereof, I have hereunto set my hand, this 17th day of May, 1929.

EVAN C. HARTER.
